CLAIM

The ornamental design for a clip, as shown and described.

DESCRIPTION

FIG. 1 is a first perspective view of a clip showing my new design;

FIG. 2 is a second perspective view thereof;

FIG. 3 is a left side view thereof;

FIG. 4 is a right side view thereof;

FIG. 5 is a rear view thereof;

FIG. 6 is a front view thereof;

FIG. 7 is a top view thereof;

FIG. 8 is a bottom view thereof;

FIG. 9 is a third perspective view thereof; and,

FIG. 10 is a fourth perspective view thereof.

The dash-dot-dash broken lines immediately adjacent the shaded areas represent the bounds of the claimed design while all other broken lines are directed to environment. The broken lines form no part of the claimed design.

1 Claim, 10 Drawing Sheets(56)
